UNITED STATES PATENT OFFICE.

DAVID R. KEITH, OF FORT SCOTT, KANSAS.

FURNACE.

1,121,508.

Specification of Letters Patent. Patented Dec. 15, 1914.

Application filed February 25, 1914. Serial No. 821,049.

To all whom it may concern:

Be it known that I, DAVID R. KEITH, a citizen of the United States, residing at Fort Scott, in the county of Bourbon and State of Kansas, have invented new and useful Improvements in Furnaces, of which the following is a specification.

This invention relates to improvements in furnaces, especially force draft furnaces and with reference to the provision of improved means for promoting combustion of the gases generated in the fire box so as to increase the heating capacity of a furnace and consume the smoke, one object of the invention being to effect improvements in the construction of the bridge wall so as to cause the gases passing from the fire box to be superheated and consumed; another object being to provide improved means for introducing air in at the bridge wall and at the rear of the fire box and above the bed of fuel therein and to heat such air so as to cause it to readily unite with the gases and render the latter combustible; another object being to provide improved means for automatically cutting off the supply of air to the ash pit and under the grate bars while the furnace door is open, as when stoking the furnace, another object being to provide improved means for regulating the supply of superheated air to the rear portion of the fire box.

The invention consists in the construction, combination and arrangement of devices hereinafter described and claimed.

In the accompanying drawings:—Figure 1 is a front elevation of a furnace constructed in accordance with my invention. Fig. 2 is a detail sectional view on the plane indicated by the line *a*—*a* of Fig. 3. Fig. 3 is a vertical longitudinal sectional view of the furnace on the plane indicated by the line *b*—*b* of Fig. 1. Fig. 4 is a vertical transverse sectional view of the same on the plane indicated by the line *c*—*c* of Fig. 3. Fig. 5 is a detail horizontal sectional view on the plane indicated by the line *d*—*d* of Fig. 3 and showing the construction and arrangement of baffle piers on the bridge wall. Fig. 6 is a detail longitudinal sectional view of the pipe which supplies heated air to the rear portion of the fire box and of the tubular valve which regulates the intake of air

by said pipe. Fig. 7 is a detail elevation of the valve operating devices, with the front furnace wall partly in section.

The furnace here shown for the purposes of this specification is a boiler heating furnace but the furnace may within the scope of my invention be of any suitable construction and used for any purpose. The boiler is indicated at 1, the furnace side walls are indicated at 2, the front wall at 3, the bridge wall at 4, the ash pit at 5, the fire box at 6, and the grate bars at 7. Preferably the grate bars are of the hollow force draft type but may within the scope of my invention be of any suitable construction. In rear of the fire box is a secondary combustion chamber 8 in which such gases as escape combustion in the fire box are consumed. The ash pit doors are indicated at 9 and the fuel doors at 10.

In accordance with my invention I provide an air supply duct 11 which is here shown as having a horizontally arranged forwardly extending lower intake arm 12 and a vertical uptake arm 13, the said uptake arm being arranged in a recess in the wall 3 and having an opening 14 on its rear side at its upper end for discharging air directly into the ash pit 5 and under the grate bars to supply fuel on the grate bars and in the fire box or combustion chamber with the air necessary to cause the fuel to burn. I also provide an oxygenating duct to supply air to the fire box at a point above the bed of fuel and at the rear end of the fire box to render such gases as would otherwise escape combustion in the fire box or combustion chamber combustible and insure their ignition and consumption in the furnace and thus increase the heating capacity of the furnace, effect an economy in fuel and prevent the furnace from discharging smoke. This oxygenating duct is here shown as comprising an air supply pipe 15, a retort chamber 16 and a discharge block 17. The retort chamber is constructed in the bridge walls and comprises a lower horizontal intake arm 18 and a vertical uptake arm 19. The discharge block 17 is made of refractory material and is built in the front side of the bridge wall at a point to the rear and at a suitable distance above the grate bars and is provided with a series of

2
forwardly and upwardly extending and forwardly contracting discharge openings 20, the rear ends of said discharge openings communicating with the uptake of the retort chamber and the front ends of said discharge openings being at the rear end of the fire box or combustion chamber 6.

5 The upper side 21 of the bridge wall inclines upwardly and rearwardly from the fire box to form a rearwardly contracting throat passage 22 under the boiler 1 and between the fire box or combustion chamber 6 and the secondary combustion chamber 8 and in this throat is arranged a series of 10 baffle piers 23-24 which are built on the top of the bridge wall and are preferably constructed of fire brick or other suitable refractory material. The front baffle piers 23 are spaced apart and the rear baffle piers 24 are arranged in line with the centers of the 15 spaces between the front baffle piers so that the said baffle piers 23-24 are arranged in staggered relation so that gases passing rearwardly from the fire box through the throat 20 22 are deflected and given a tortuous course 25 by the said baffle piers thus causing the gases to be thoroughly mixed and the said baffle piers being highly heated to cause said gases to be also superheated so that they become 30 consumed in the secondary chamber. The air which is supplied to the rear portion of the fire box, above the bed of fuel through the oxygenating duct is also highly heated during its passage through the retort chamber 35 16 and the block 17 and such highly heated air being discharged into the gases in the combustion chamber of the fire box 6 becomes mingled with the gases and renders them highly combustible. Hence the gases 40 arising from the heated fuel are consumed, partially in the fire box and finally in the secondary combustion chamber, thus utilizing the fuel to the fullest extent effecting an economy in the fuel and preventing 45 smoke.

The air supply pipe 15 which constitutes 50 an element of the oxygenating duct is arranged longitudinally in the fire box, extends through the uptake 13 of the air duct 11 and also through the front wall 3 of the chamber and has a bearing in the front wall, also has bearings in the uptake of the air duct 11 and the rear portion of said pipe, which extends into the arm 18 of the retort 55 chamber 16 has a bearing as at 25 in a plate 26 which closes the front end of said intake arm 18 of the retort chamber. This plate has air inlet openings 27 27^a which lead directly from the rear end of the ash pit 5. 60 The pipe 15 is provided at its front end with a crank arm 28 by means of which it may be turned or oscillated in its bearings and the said pipe is also provided near its rear end, with a shutter valve 29 which projects from the said pipe 15, at right angles

thereto and is adapted to close and uncover the opening 27^a according to the direction in which said pipe 15 is turned.

65 A damper 30 is secured to the pipe 15 to be turned therewith and is arranged in the uptake of the air supply duct 11. This damper is arranged at right angles to the shutter valve 29 so that when the damper is in horizontal position to close the uptake of the air duct 11 and cut off the supply of air to the 75 ash pit, the shutter valve 29 is in position to close the opening 27 thereby cutting off the supply of air to the retort chamber 16 through the opening 27 and from the ash pit.

80 In the pipe 15 is a tubular valve 31 which is arranged to be partly turned in said pipe 15 and is closed at its front end as at 32. The pipe 15 has an air intake opening 32 in the uptake of the air duct 11 and on the side opposite the damper 30. The tubular valve 31 has a similar opening 34 which may be turned into and out of registry with the opening 33. Said opening extends about halfway across the pipe 15, and 31. At the front end of the tubular valve 31 is an arm 36 which projects therefrom at right angles thereto and is arranged on the front side of the front wall 3. A guide 37 projects from said wall and an operating rod 36^a travels in said guide and is attached to the arm 36 and 90 may be used for partly turning the tubular valve. The tubular valve being connected by the pipe 15 turns with said pipe and is also adapted to be turned independently thereof so that the opening 33 may be closed 100 by the valve 31 whenever this is desired. At the rear end of the tubular valve is a shutter valve 35 for uncovering or closing the opening 27^a.

105 Each fire door 10 is provided with a tappet arm 38. A horizontally arranged shaft 39 which is parallel with the front wall 3 and arranged at a suitable distance above the fire doors is mounted in bearings 40 with which a bracket 41 is provided, the said 110 bracket being secured on the front side of the wall 3. This shaft 39 is provided near its ends with rock arms 42 which may be moved into and out of engagement with the tappet arms of the fire door. The said shaft 115 also has a lever 44 by means of which it can be turned and the said lever is connected by a rod 45 to a link 45^a that operates in guides 45^b. A rod 45^c connects said link to the arm 28 of the pipe 15.

120 When the fire doors are closed the damper 30 is in open position and the shutter valves 29 and 35 are in position to respectively uncover the openings 27-27^a and the openings 33-34 are also in registry. This allows air to pass out above the fuel bed and into direct contact with the smoke, returning it over the fuel bed and causing the smoke to be consumed. When the rod 36^a is moved downwardly through about one 130

half the extent of the limit of its movement, the tubular valve 31 will be turned sufficiently to cause the opening 33 in the pipe 15 to be closed but not to a sufficient extent to cause the opening 27^a to be closed by the shutter valve 35. When said rod is moved downwardly to the full extent the said opening 27^a will be closed by the shutter valve 35, the opening 33 remaining closed but the damper 30 and the shutter valve 29 will remain in open position. When a fire door is opened the lever 44 will be automatically turned and through its connections 45^a and 45^b and the arm 28 will partly turn the tube 15, thus closing the damper 30 and also closing the opening 27 by the shutter valve 29. This cuts off the supply of air to the fire while stoking. This movement of the pipe 15 however, will cause its opening 33 to register with the opening 34 of the tubular valve and hence air will be supplied to the fire, above the grate, through said tubular valve and the chamber 16 as will be understood. When the door is closed the pipe 15 in turning the opening 27 will cause the tubular valve to turn therewith and the ports 33—35 and 27 will be open to supply air to the chamber 16. When thus arranged the furnace is in maximum operating condition. When it is desired to check the fire the rod 36^a can be operated to partly turn the tubular valve to cause the shutter valve 37 to close the opening 27^a and to also cause the tubular valve to close the opening 27^a. The lever 44 may be manually operated to turn the pipe 15 and hence cause the damper 30 to be moved to closed position while the openings 33—34 will register and thus admit air to the chamber 16. The closing of the damper 30 when the fuel doors are open prevents an excessive amount of cold air from entering through the fuel door owing to the check on the draft occasioned by such closing of the damper.

Air supplied from below the grate bars through the air duct 11 and the ash pit, in connection with the air supplied to the rear end of the fire box above the bed of fuel through the oxygenating duct, causes the unconsumed gases which arise from the fire immediately after the latter has been supplied with fuel to become commingled with the superheated air supplied by the oxygenating duct, and as the mixture passes over the bridge wall and between the baffle and superheated piers it will be ignited in the combustion chamber thus preventing smoke and causing the gases to give out their calorific.

Having thus described my invention, I claim:

1. A furnace having a fire box, a grate therefor, an ash pit, an air duct discharging into the ash pit, an oxygenating duct connecting the air duct and the rear portion

of the fire box, at a point above the grate, said oxygenating duct including a tubular element mounted for oscillatory movement and extending into the air duct, a damper for the air duct carried by and movable with said tubular element and means to turn said tubular element and said damper to control the intake of air through the air duct.

2. A furnace having a fire box, a grate 75 therefor, an ash pit, an air duct discharging into the ash pit, an oxygenating duct connecting the air duct and the rear portion of the fire box, at a point above the grate, said oxygenating duct including a tubular 80 element mounted for oscillatory movement and extending into the air duct, a damper for the air duct carried by and movable with said tubular element and means to turn said tubular element and said damper 85 to control the intake of air through the air duct and means to open or cut off communication between the said tubular element and the air duct.

3. A furnace having a fire box, a grate 90 therefor, an ash pit, an air duct discharging into the ash pit, an oxygenating duct connecting the air duct and the rear portion of the fire box, at a point above the grate, said oxygenating duct including a tubular 95 element mounted for oscillatory movement and extending into the air duct, a damper for the air duct carried by and movable with said tubular element and means to turn said tubular element and said damper, and a 100 valve also operated by said tubular element to open or close and cut off communication between the ash pit and said oxygenating duct.

4. A furnace having a fire box, a grate 105 therefor, an ash pit, an air duct discharging into the ash pit, an oxygenating duct connecting the air duct and the rear portion of the fire box, at a point above the grate, said oxygenating duct including a tubular 110 element mounted for oscillatory movement and extending into the air duct, a damper for the air duct carried by and movable with said tubular element and means to turn said tubular element and said damper, and a 115 valve also operated by said tubular element to open or close and cut off communication between the ash pit and said oxygenating duct, a fire door and means operated by the fire door to actuate said tubular element and 120 said damper.

5. A furnace having a fire box, a grate 125 therefor, an ash pit, an air duct discharging into the ash pit, an oxygenating duct connecting the air duct and the rear portion of the fire box, at a point above the grate, said oxygenating duct including a tubular element mounted for oscillatory movement and extending into the air duct, a damper for the air duct carried by and movable with 130

4
said tubular element and means to turn said tubular element and said damper, and a valve also operated by said tubular element to open and cut off communication between 5 the ash pit and said oxygenating duct, a fire door and means operated by the fire door to actuate said tubular element and said damper and valve.

6. A furnace of the class described having 10 a fire box, a grate therefor, an ash pit below the grate, an air duct discharging into the ash pit, an oxygenating duct leading from the air duct to the rear portion of the fire box at a point above the grate and including 15 a tubular element extending across the air duct and mounted for oscillatory movement, said tubular element having an air inlet opening arranged in said air duct, a damper for the air duct carried by and movable with 20 said tubular element, means to turn said tubular element, a valve to open and close the air intake opening of said tubular element and means to operate said valve.

7. A furnace of the class described having 25 a fire box, a grate therefor, an ash pit below the grate, an air duct discharging into the ash pit, an oxygenating duct leading from the air duct to the rear portion of the fire box at a point above the grate and including 30 a tubular element extending across the air duct and mounted for oscillatory movement, said tubular element having an air inlet opening arranged in said air duct, a damper for the air duct carried by and 35 movable with said tubular element, means to turn said tubular element, a valve to open and close the air intake opening of said tubular element and means to operate said valve.

40 8. A furnace of the class described having a fire box, a grate therefor, an ash pit below the grate, an air duct discharging into the ash pit, an oxygenating duct lead-

ing from the air duct to the rear portion of the fire box at a point above the grate 45 and including a bypass leading thereto from the ash pit and also including a tubular element extending across the air duct and mounted for oscillatory movement, said tubular element also having an air inlet opening arranged in said air duct, a damper for 50 the air duct carried by and movable with the tubular element, means to turn said tubular element, a valve to open and close the air intake opening of said tubular element 55 and means operated by said valve to open and close said bypass.

9. A furnace of the class described having a fire box, a grate therefor, an ash pit below the grate, an air duct discharging into the 60 ash pit, an oxygenating duct leading from the air duct to the rear portion of the fire box, at a point above the grate and including a pair of bypasses leading thereto from the ash pit, said oxygenating duct also including a tubular element extending across the air duct and mounted for oscillatory movement, said tubular element having a valve to open and close one of said bypasses 65 and also having an air intake opening arranged in said air duct, a damper for the air duct carried by and movable with the tubular element, means to turn said tubular element, a tubular valve to open and close the air intake opening of said tubular element and arranged for oscillatory movement with respect to said tubular element, and means operated by said valve to open 70 and close the other bypass.

In testimony whereof I affix my signature 80 in presence of two witnesses.
